(57) **CLAIM**

The ornamental design for a faucet, as shown and described.

DESCRIPTION

FIG. 1 is a first perspective view of a faucet showing the claimed new design;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detail view of a component with a label number "9" in FIG. 1; and,

FIG. 10 is an enlarged detail view of a component with a label number "10" in FIG. 2.

The broken lines shown in the drawings are for the purpose of illustrating environment that form no part of the claim. The dot dash broken lines indicate cutoff boundaries for enlarged detailed portion views and form no part of the claim.
